UNITED STATES PATENT OFFICE

114,680

DESIGN FOR A MITTEN

Kathryn Dallas Henderson, New York, N. Y.

Application April 3, 1939, Serial No. 84,008

Term of patent 3½ years

To all whom it may concern:

Be it known that I, Kathryn Dallas Henderson, a citizen of the United States, residing at New York, in the county and State of New York, have invented a new, original, and ornamental Design for a Mitten, of which the following is a specification, reference being had to the accompanying drawing, forming part thereof, wherein

Fig. 2 is a back view thereof.

I claim:

The ornamental design for a mitten, substantially as shown.

KATHRYN DALLAS HENDERSON.
